CLAIM

The ornamental design for a syringe, as shown and described.

DESCRIPTION

FIG. 1 is a front perspective view of a syringe showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

Oblique line shading represents portions of our new design that are transparent or translucent.

Solid gray shading represents a color contrast in the sense that the portions of our new design so shaded, which may be any “color”, for example, red, blue, green, or yellow, are in color contrast with the transparent or translucent portions of our new design.

In FIGS. 1-6 and 8, the solid gray shading varies in tone and thus includes light solid gray shading and dark solid gray shading. The light solid gray shading represents the solid gray shaded portions of our new design when viewed through the transparent or translucent portions of our new design. The dark solid dark gray shading represents the solid gray shaded portions of our new design when not viewed through the transparent or translucent portions of our new design.
